UNITED STATES PATENT OFFICE.

LAURA WINN, OF CHICAGO, ILLINOIS.

SANITARY SEMISKIRT.

1,164,970.

Specification of Letters Patent. Patented Dec. 21, 1915.

Application filed November 24, 1914. Serial No. 873,690.

To all whom it may concern:

Be it known that I, LAURA WINN, a citizen of the United States, residing at Chicago, in the county of Cook and State of Illinois, have invented certain new and useful Improvements in Sanitary Semiskirts; and I hereby declare that the following is a full, clear, and exact description thereof, reference being had to the accompanying drawings, which form part of this specification.

This invention is an improved underskirt for ladies' wear; and its object is to provide a sanitary combined semi-skirt and apron which may be used as an underskirt and protector, with or without other underskirts.

The objects of the invention are to provide a garment of this character which can be readily adjusted, will fit neatly, and can be easily laundered.

The novel semi-skirt is intended for an article that can be worn at all times and on all occasions, where no other petticoat is worn, or to protect other dainty undergarments being soiled from perspiration or menstruation.

The semi-skirt has an absorbent portion next to the body and is a far more comfortable garment for wear during menstruation periods than the ordinary rubber cloth aprons which are uncomfortable after being worn a few hours, because they do not absorb moisture and become quite slushy and uncomfortable. My novel semi-skirt prevents this discomfort and can be worn at any time and all the time and will take the place of the non-petticoat, and can be worn with or without other skirts.

The novel semi-skirt is adjusted easily by entirely opening the garment and fastening it at the right side with a button at the lower edge and tie at the waistband; the supporters are fastened to the hose and adjusted; and the rubber apron can be detached for washing.

I will describe the semi-skirt as illustrated in the accompanying drawings in which—

Figure 1 is a side view of the semi-skirt in use. Fig. 2 is a view of the semi-skirt opened. Fig. 3 is a detail sectional view on line 3—3, Fig. 2.

The garment consists of front and rear skirt portions 1 and 2 which are preferably made of fabric such as "bird's-eye" crepe, poplin or silk cloth, and are united at one

side, say at what would be the left side of the wearer when the garment is worn, as shown at 1^a; the opposite side edges of such portions are hemmed as shown at 1^b, 60 2^b; and are provided with suitable detachable fastenings, a button and button-hole being indicated at 1^c, 2^c. The upper ends, or waist portions of these parts 1 and 2 are fitted with darts and provided with casing 65 hems 1^d, 2^d, which casing may be continuous, and through this casing is passed a drawing string 3, by which the semi-skirt can be fastened around the corset and waist of the wearer in the usual manner.

The semi-skirt when worn is closed to a point below the hips, and is practically slit at both sides, as indicated in Figs. 1, and 2. The lower edges of the semi-skirt portion may be trimmed in any desired manner.

Attached to the rear portion 2 of the semi-skirt is a waterproofed apron 4 preferably made of rubber cloth and which is shorter than the rear portion and may be stitched thereto or fastened on with buttons or clasps such as glove fastenings, at its upper end, as indicated at 4^a, to make a neat close fitting seam or fastening connection therebetween. The upper end of the said apron is 80 below the waist portion of the semi-skirt, as indicated in the drawings. The rubber face of said apron 4 is preferably placed against the opposed face of the cloth portion 2, so it will be kept from directly contacting with 85 the wearer by said portion 2. To each side of this apron, near its upper end, is attached a strap 5 which is preferably elastic, and extends diagonally to the apron edge; and when the semi-skirt is worn each strap can 90 be passed partly around the leg of the wearer and attached to the stocking and be used both as a stocking supporter and to hold the apron and rear portion of the semi-skirt neatly and properly in position. The straps 95 5 are adapted to be passed through tape loops 2^a attached to the side edges of the rear portion 2 so that when the apron is fastened the rear portion will also be properly positioned. As shown the said straps 5 are 100 provided with the usual stocking engaging devices 6; and the lower ends of these straps are passed through the loops 6^a of the hose supporting devices and attached to a clamp slide 6^b, of ordinary construction, on the 105 strap so that the straps can be adjusted in length to suit the wearer.

Some of the advantages of this garment have been above explained, and other advantages thereof will be appreciated by women; and the manner of wearing same 5 will be readily understood by them from the foregoing explanation and drawings.

What I claim is:

1. The herein described semi-skirt and protector comprising front and rear portions, 10 and means for securing same to the waist of the wearer, a waterproof apron attached to the exterior of the rear portion of the skirt, straps connected to the sides of said apron and adapted to extend partly around 15 the legs of the wearer to confine the said apron in position relative to the body of the wearer and provided with means to detachably secure their free ends, and means whereby the rear portion of the apron is 20 also connected with said straps and held in position thereby.

2. A semi-skirt and protector comprising an absorbent fabric portion, means for securing same to the waist of the wearer, and 25 loops attached to opposite side edges of said portion; a waterproof apron attached to the said portion; and securing straps attached to the sides of said apron and passing through said loops and adapted to extend

partly around the legs of the wearer to hold 30 the apron in position, said straps being provided with devices by which they may be secured in place.

3. The herein described semi-skirt and protector comprising front and rear fabric 35 portions united at one side and open at the opposite side, means for securing such skirt to the waist of the wearer, fastening devices for detachably uniting the adjacent edges of said portions at the open side, a waterproof 40 apron attached to the rear portion of the skirt, and straps attached to opposite sides of the said apron and passing through loops on the adjacent edges of the rear fabric portion and adapted to extend partly around 45 the legs of the wearer to hold the apron in position, said straps being provided with devices by which they can be engaged with the hose of the wearer to hold the straps and apron in position.

In testimony that I claim the foregoing as my own, I affix my signature in presence of two witnesses.

LAURA WINN.
